ADVERTISING DISPLAY DEVICE

Allan Friedman, Brooklyn, and Benjamin S. Colnes, Mount Vernon, N. Y.

Application March 15, 1938, Serial No. 195,936

4 Claims. (Cl. 40—124.1)

This invention relates to advertising display devices, and more particularly to advertising cards bearing in relief, facsimiles of various types of articles.

5 One object of the invention is the provision of a device of this character made of a single sheet of rectangular material such as paper, cardboard, or the like, from which is formed a self-standing frame and a figure in simulation of an article 10 such as a can or the like.

Another object of the invention is the provision of such a device from a single sheet of flexible material without necessarily wasting any portion thereof, and to which no additional parts are 15 necessary to complete the device.

A further object of the invention is the provision of a device of this nature which may be readily and securely erected into display position from collapsed flat condition by contracting 20 same in a horizontal direction, said contraction acting to bring a portion of the blank from which the device is made into relief in simulation of an article, and to flex the blank so as to enable the device to stand erect upon the bottom edge thereof 25 of without any additional support.

25 Another object is to produce a device of the character described in which the maximum simplicity of construction and operation is secured.

Other objects and advantages will appear as 30 the nature of the improvements is better understood, the invention consisting substantially in the novel arrangement and co-relation of parts herein fully described and illustrated in the accompanying drawings, wherein similar reference 35 characters are used to describe corresponding parts throughout the several views, and then finally pointed out and specifically defined and indicated in the appended claims.

The disclosure made the basis of exemplifying 40 the present inventive concept suggests a practical embodiment thereof, but the invention is not to be restricted to the exact details of this disclosure, and the latter, therefore, is to be understood from an illustrative, rather than a restrictive stand-point.

45 In the drawings forming a part of this application,

Figure 1 is a perspective view of one form of our improved device;

50 Figure 2 is a plan view of the blank from which the device is made;

Figure 3 is a top plan view of the device showing same flexed in the opposite direction to that shown in Figure 1;

55 Figure 4 is a perspective view of a modified form of our invention, and

Figure 5 is a plan view of the blank from which the same is made.

Referring now to Figures 1 to 3 of the drawings 60 in detail 10 indicates an advertising display de-

vice made from a single rectangular sheet of material such as cardboard or the like. The device is formed by providing the blank with an upper horizontal cut 12, a lower horizontal cut 13 parallel to the cut 12, the cuts 12 and 13 are 5 of equal length and extend between vertical score lines 14 and 15 spaced from the blank end edges 16 and 17 respectively. Spaced from the cut or severance line 12 is a cut 18 parallel thereto but considerably shorter in length, a cut 19 of 10 the same length as the line 18 and parallel thereto is provided a short distance above the cut 13, the said lines 18 and 19 extending between a pair of vertical score lines 20 and 21, the cuts 18 and 19 and the score lines 20 and 21 forming a 15 central area 22.

The area bound by the score lines 14 and 15 and the cut lines 12 and 13 is divided into a pair of walls or panels 23 and 24 by means of vertical cuts 25 and 26 extending respectively between 20 the cuts 12 and 18, and 13 and 19, the said cuts 25 and 26 being in line and centrally located with respect to the end edges 16 and 17 of the blank. A marginal frame is formed all around the device by the score lines 14, 15 and the cuts 25 25 12 and 13, said frame comprising vertical side sections 28 and 29 and upper and lower horizontal sections 30 and 31. Spaced from the central vertical cuts 25 and 26 respectively are upper vertical cuts 32 and 33 and lower vertical cuts 30 34 and 35.

To erect the device for counter or show window display the blank 11 may be placed upon the bottom edge thereof and the panels 23 and 24 may be brought forwardly or rearwardly of 35 the marginal frame and drawn together, this drawing together of the panels 23 and 24 will cause the central area 22 to bulge outwardly into a semi-cylindrical formation 22a as shown in Figures 1 and 3 and the said contraction will 40 further cause the upper and lower marginal frame sections 30 and 31 to bulge forwardly or rearwardly of the panels 23 and 24. The bulge thus formed at the lower marginal section providing a stable support for the device. When 45 fully drawn together the panels 23 and 24 are interlocked by means of the cuts 32, 33, 34 and 35.

It is to be understood that the front surface of the device may have suitable advertising matter printed thereon and the bulging can or cylindrical portion 22a may have a suitable label superposed or directly printed thereon to simulate any particular brand of merchandise.

It is further to be understood that instead of a semi-cylindrical bulge an angular bulge may 55 be provided to simulate a package or the like, such angular bulges being provided by the introduction of suitably spaced apart score lines in the area 22.

In Figures 4 and 5 of the drawings we have 60

shown a modified form of the invention wherein the panels from which the article simulated is bent, is set back from the marginal end sections, so that the entire device may be placed on display 5 directly behind the glass of a show window.

In this latter form of our invention the blank 11a from which the display device 10a is made, is provided with the same vertical and horizontal cuts as the form of our invention described above 10 with the addition of vertical score lines 40 and 41, the score line 40 being intermediate the score lines 14 and 20, and the score line 41 being between the score lines 15 and 21 thus providing in addition to the central panels 23a and 24a 15 two side panels designated in Figures 4 and 5 of the drawings as 42 and 43. The horizontal frame portions of the device is divided by upper and lower score lines 44 and 45 into sections 46 and 47 respectively, the said score lines being 20 preferably centrally located with respect to the end edges 16 and 17 of the blank.

In erecting the modified form of our improved device, instead of flexing the top and bottom marginal portions 46 and 47 they will hinge about 25 the score lines 44 and 45 to produce the bulged effect. Likewise the panels 42 and 43 being articulate about their respective score lines 14, 40 and 15, 41 will assume an angular position with 30 respect to the central panels and vertical marginal frame portions thus effecting the desired set back of the simulated bulged article 22a.

From the foregoing it will be seen that we have provided a simple, inexpensive advertising display device made from a single sheet of flexible 35 material of standard size without necessarily wasting any portion thereof and without the addition of any material thereto, and one that will stand erect upon its bottom marginal edge without the provision of any addition or auxiliary supporting means.

It will likewise be seen that the blanks may be shipped and stored in flat position and erected where and when desired.

It will be understood that wherever in the 45 specification we refer to the central area, we are not to be limited to the precise position shown in the drawings, as the positioning of this area may be varied, and that the relative positions of the various cuts and scores hereinabove referred to may also, within reasonable limits, be differently located than as indicated in the drawings, so as to produce a substantially similar or equivalent article without departing from the spirit of 50 our invention, and the scope of the appended claims.

It should also be noted that the various scores and cuts as shown in the drawings may be made at an angle to the base, and not necessarily parallel or perpendicular to the base.

Having described our invention what we claim 60 as new and desire to secure by Letters Patent is:

1. An advertising display device made from a single sheet of material of regular contour, the 65 said device comprising a marginal frame having vertical and horizontal marginal portions, a pair of spaced apart vertical score lines each score line being spaced from the end edge of its respective vertical marginal frame portion, a pair of spaced apart horizontal cuts extending between the said vertical score lines, the said cuts being spaced 70 from the top and bottom edges of the respective horizontal marginal frame portions, a second pair of spaced apart horizontal cuts spaced inwardly from the first mentioned horizontal cuts and of

shorter length than the said first mentioned cuts, a pair of spaced apart vertical score lines connecting the ends of the said second mentioned cuts, an area formed between the said second mentioned horizontal cuts and vertical score lines for simulating an article of merchandise, an upper vertical cut extending between the upper horizontal cuts, a lower vertical cut extending between the lower horizontal cuts, and means on each side of the vertical cuts for interlocking the 10 portions of the device on either side of the said vertical cuts. 5

2. An advertising display device made from a single sheet of material of regular contour cut and scored to define a central area, a panel on each side of the said area completely surrounding the said central portion and movable towards each other, top, bottom and end marginal frame portions surrounding the aforementioned panels, the bottom edge of the bottom frame portion 20 forming a bulged support for the device when the panels are moved towards each other, the central area forming a bulge in simulation of an article of merchandise when the panels are so moved, and locking means on the panels for interlocking same when the central portion is in bulged position. 25

3. An advertising display device made from a single sheet of material of regular contour, the said device comprising a marginal frame having vertical and horizontal marginal portions, a pair of spaced apart vertical score lines each score line being spaced from the end edge of its respective vertical marginal frame portion, a pair of spaced apart horizontal cuts extending between the said vertical score lines, the said cuts being spaced from the top and bottom edges of the respective horizontal marginal frame portions, a second pair of spaced apart horizontal cuts spaced inwardly from the first mentioned horizontal cuts and of shorter length than the said first mentioned cuts, a pair of spaced apart vertical score lines connecting the ends of the said second mentioned cuts, an area formed between the said second mentioned horizontal cuts and vertical score lines for simulating an article of merchandise, an upper vertical cut extending between the upper horizontal cuts, a lower vertical cut extending between the lower horizontal cuts, a vertical score line extending between the upper edge of the blank and the uppermost cut, a vertical score line extending between the lowermost cut and the lower edge of the blank, and means on each side of the vertical cuts for interlocking the portions of the device on either side of the said vertical cuts. 40 45

4. An advertising display device made from a single sheet of material of regular contour cut and scored to define a central area, a panel on each side of the said area completely surrounding the said central portion and movable towards each other, a second panel adjoining each of the first mentioned panels, top, bottom and end marginal frame portions surrounding the aforementioned panels, the bottom edge of the bottom frame portion forming a bulged support for the device when the panels are moved towards each other, the central area forming a bulge in simulation of an article of merchandise when the panels are so moved, and locking means on the panels for interlocking same when the central 50 55 portion is in bulged position. 60 65 70
